CLAIM

The ornamental design for a dispenser for tissue glue, as shown and described.

DESCRIPTION

FIG. 1 is a perspective view of a dispenser for tissue glue showing my new design, with the lid in open position; FIG. 2 is a perspective view thereof, with the lid shown in closed position;

FIG. 3 is a bottom perspective view thereof, with the lid in open position;

FIG. 4 is a perspective view thereof, with the lid shown in closed position; and,

FIG. 5 is an end elevational view thereof.
